UNITED STATES PATENT OFFICE.

OSCAR L. SMITH, OF GRAND RAPIDS, MICHIGAN.

DISPLAY DEVICE.

1,161,902.

Specification of Letters Patent. Patented Nov. 30, 1915.

Application filed June 19, 1912. Serial No. 704,607.

To all whom it may concern:

Be it known that I, OSCAR L. SMITH, a citizen of the United States, residing at Grand Rapids, in the county of Kent and State of Michigan, have invented an Improvement in Display Devices, of which the following description, in connection with the accompanying drawings, is a specification, like numbers on the drawings representing like parts.

The invention to be hereinafter described relates to display devices and more particularly to such devices as are employed to display merchandise, such as ready-made garments, in stores and the like.

In devices of this general character it is desirable that a case or cabinet be employed and that it be formed in large part, at least, of glass. A rotatable rack has heretofore been mounted for movement to and from a position within the case or cabinet, so that when in outer position the rack, upon which the merchandise or garments were supported, could be rotated to bring all parts of the rack to the front for convenient inspection of the garments thereon, and when in inner position the doors of the case or cabinet could be closed to protect the goods from dust, dirt, and unauthorized handling.

As pointed out in my prior Patent No. 987,183, dated March 21, 1911, economy of floor space consumption and other considerations dictate that the rack be of rectangular form and that the case or cabinet be of proper size to permit the rack to be economically housed within it when in inner position and to rotate, that is to turn three hundred and sixty degrees, as many times as desired when in front position. In a construction of this general character it was found that if free rotative movement of the rack, which was desirable at the front of the case, be permitted as the rack was being moved to and from its inner position, injury to the case might result, and especially would this be true when the rack was loaded with garments. To obviate this objection and yet preserve the free rotative movement of the rack when in front position, my prior patent provided that means be employed to control such free rotative movement as the rack was being moved to or from its inner position, so that such means, regardless of its particular details, would always prevent the rack from striking the case or cabinet.

This feature of the said prior patent protected the case or cabinet from injury by preventing the rack or any part thereof from striking the case or cabinet, as the rack was being moved to and from its inner position. In the present invention, however, it has been found that objectionable injury to the case or cabinet could be prevented by permitting the rack or some part connected thereto to strike the case or cabinet, provided means were employed to so control said striking contact as to overcome its injurious character; and with this fact in view the aims and purposes of the present invention are to provide a display device of general type hereinbefore noted, wherein a rotatable rack is movable to and from a position within a case or cabinet and can be rotated to present the goods thereon to inspection when at front position, and wherein also the rack or a part connected thereto or movable with the rack is permitted to strike the case or cabinet as the rack is moved to or from its inner position, and means are provided to secure for said contact a yielding of non-injurious character, all of which will best be made clear from the following description and accompanying drawings of one form of means for carrying the invention into practical effect, it being understood that the invention is not restricted to the described and illustrated details, but in its true scope is defined by the claims.

In the drawings, Figure 1 is a front view of a display device showing one form or embodiment of the present invention; Fig. 2 is a section of Fig. 1 on the line 2-2, also showing in dotted lines a convenient form of carriage or movable support for the rack; Fig. 3 is a detail of a modification to be described; Fig. 4 is a view similar to that of Fig. 2 but showing the rack in another position; Fig. 5 is a detail on an enlarged scale showing features of structure embodied by the present invention; Fig. 6 is a detail showing lugs and adjacent parts for supporting the case or cabinet contacting device; and Fig. 7 is a further detail of some of the parts of Fig. 5 showing the relative position of parts of the contacting device when one of the parts has engaged and been deflected by the case or cabinet.

The case or cabinet may be of appropriate character to contain the rack, and comprises the base 1 surmounted by glass panels 2 at

the sides and back, which may be appropriately supported at their adjacent edges. As one means for thus supporting the adjacent edges of the glass panels, suitable corner posts 3 may be employed, but these may not be necessary. The top of the case or cabinet is also preferably formed of glass, and glass panel doors 4 of suitable design may be employed for closing the front of the case or cabinet.

The base 1 of the case or cabinet may have a bottom floor or plate 5, Figs. 2 and 4, below which a carriage 6 may be mounted in suitable ways 7 below the floor or plate 5, said carriage being movable to and from a position within the case or cabinet. Since the particular form or character of carriage is not material to the present invention, it is to be understood that the carriage 6 is merely typical of some means for supporting the rack and for carrying it to and from a position within the case or cabinet.

Rising from the carriage 6 and passing through the slot 8 in the floor or plate 5 is the stud 9 for carrying the rack supporting arms 10. Said stud may be of any appropriate character well known by those skilled in the art, its purpose being to support the arms 10 and permit rotative movement of said arms and consequently the rack sustained by them.

Rising from the arms 10 are the uprights 11, 11, on which are the cross arms 12, 12, in whose outer ends are supported the rack, comprising the rods 13, 13, from which the garments or other merchandise are hung. Said rods 13, 13, are preferably connected at their outer ends by the guards 14.

From the construction thus far described, it will be noted that the case or cabinet is of general rectangular form, and that the rack, which is of like form, is mounted for movement to and from a position within the case or cabinet by virtue of the carriage or other device 6. When in outer position or at the front of the case or cabinet it will be noted that the rack can be rotated or turned horizontally through any number of degrees to bring all the parts of the rack to front position for inspection of the garments, cleaning or other purpose, and that when moved back into the case or cabinet that the rack or rods 13, 13, take position substantially parallel to the back wall of the case or cabinet.

In the movement of the rack to and from its inner position, it is liable to strike the case or cabinet, and in the absence of means to prevent, would probably break the glass or so injure the structure as to render repair necessary.

In my prior patent this injurious contact of the rack with the case or cabinet as the rack was moved to and from its position within the case or cabinet, was obviated by

controlling or limiting the rotative movement as the rack was being moved to and from its position within the case or cabinet, and as one form of means to that end a lock was shown which held the rack from rotative movement when away from front position. The present invention, however, contemplates a permissive contact of the rack or a part connected to or movable with it against the case, but provides means to render said contact non-injurious to the case, so that in the present invention no locking means need be provided for the rotatable rack, and should the rack strike the case or the glass panels thereof, regardless of the position of the rack at such time, such contact will not cause injury to the case. Various forms of means may be employed to carry this feature of the invention into effect, but the following has been found well adapted to the intended purposes.

The rack supporting arms 10 are preferably lengthened to provide bearing portions for a yielding device, which has capacity to yield, should such device be moved into contact with the case or cabinet, regardless of the position of the rack at such time. In other words, should the rack be moved toward inner position when partially turned as in Fig. 4, the yielding device will contact with the wall of the case or cabinet, but owing to its character and construction, it will give under the movement of the rack and not injure or break the case or cabinet. Similarly, should the rack be moved inward when it is at right angles to the back wall of the case or cabinet, the yielding device will again give under the movement of the rack and prevent injury to the case or cabinet. These are merely examples in two positions, of how the device may act to permit contact with the case and yet prevent injury resulting therefrom, and it is to be understood that like action will result should the device strike the case or cabinet at any position of the rack. Having described the general character of the device, description will now be given of one form of means for carrying the invention into effect.

The bearing portions of the arms 10 are preferably formed as sockets 15, shown enlarged in Fig. 5, in which is a plunger 16 having a pin 17 extending into a socket or recess 18, Fig. 5. Surmounting the pin 17 is a spring 19 disposed between the end of the plunger 16 and the bottom of the socket 15, the construction being such that the plunger 16 will be normally forced outward by the spring but may be forced inward against the spring tension, as will be clear to those skilled in the art. A cross pin 20 secured to the pin 17 may limit the movement of the plunger 16, as indicated in Fig. 5, but the details of this feature, as well as others described are not material,

and may be varied within the true scope of the actual invention.

Pivotedly mounted to the outer position of the plunger 16, as between the lugs 21, 21, 5 Figs. 5 and 6, is the pivotal portion of the contact device, which, as shown by Figs. 2, 4 and 5 may comprise the arms 23, 24, pivoted at 25. These contact arms are held 10 yieldingly in normal position, indicated by Fig. 5, wherein, each arm has a short extension, on the opposite side of the pivotal point 25 from its acting end portion, to which is connected one end of a spring 26 as at 27, the other end 28 of said spring being 15 connected at 29 to the extensions of the arms 10. In order that the springs 26 may maintain the contact arms in desired normal position, the plunger 16 between the lugs 21, 21, has shouldered portions 30 against which 20 the short extensions of the contact arms are held by said springs.

Each of the contact arms 23 and 24 is preferably provided with a cushion, such as the rubber or other strip 31, the edge portions of which may be let into the edge surfaces of the contact arms; and the acting end portions of these contact arms at 32 are preferably rounded and covered by the cushions 31, as indicated.

From the construction described, it will be apparent that when the rack has been moved to its front position, it may be rotated through as great an angle as desired, and when it is desired to push the rack to its inner position, it may be forced back without first lining the rack up into parallel relation with the case or cabinet. In this backward movement, the rack may assume any position relative to the case from parallel therewith to a position at right angles thereto, and if pushed back when not parallel to the case, as for instance, when inclined with reference thereto, as shown by Fig. 4, one of the contact arms 23 or 24 will strike the case and yield against the tension of its spring 26, whereupon said spring 26 will re-act upon the rack through its contact arm and swing or tend to swing the rack into position indicated by Fig. 2. Should the rack be pushed inward when perpendicular to the back wall of the case or cabinet, both of the contact arms 23 and 24 will contact with the wall of the case adjacent the pivot 25, and thereby press the plunger 16 inward without causing injury to the case, it being noted that the combined strength of the springs 26 is less than the expansive force of the spring 19. Thus it will be noted that while the rack or a part connected with the rack may strike the case or cabinet as the rack is moved to or from inner position, means are provided to secure a yielding or non-injurious contact between the case and rack mechanism in whatever position the rack may be with relation

to the case when the said contact takes place. Obviously also, should the rack or part connected thereto strike the case as the rack is being moved to front position, the same yielding and non-injurious character of contact will take place, so that even though the glass walls of the case may be struck by the rack or a part connected thereto and no means is employed to prevent, such contact in any position of the rack is of a yielding and non-injurious character.

Instead of making the contact arms separate and pivoting them on the plunger 16, as described, said arms may be made as one or integral, Fig. 3, and such single or integral 80 arm 35 may be pivoted centrally as at 36, and the springs 37 be employed to balance said arm in normal position, as indicated, upon the plunger 16.

Various changes may be made in the particular means for carrying the invention into practical effect within the true scope of the invention, as I believe myself to be the first to provide a display device of the character described, wherein the rack or a part connected thereto is permitted to strike the case, and means are provided to secure a yielding or non-injurious contact between the case and the rack or rack mechanism, in whatever position the rack may be when said contact takes place.

What is claimed is:—

1. In a display device, the combination of a case, a rotatable rack having supporting bars movable to and from a position within the case, guards secured to the end portions of the rotatable rack, contact arms extending beyond the rack guards and at greater radial distance from the axis of rotation of the rack than the ends of the supporting 100 bars, and means for supporting said contact arms yieldingly from the rotatable rack to permit said arms to yieldingly contact with the case when the rack is moved into the case in any position other than parallel to the back wall of the case.

2. In a display device, the combination of a case or cabinet, a rotatable rack movable to and from a position within the case or cabinet and comprising parallel supporting 115 rods, contact members extending longitudinally beyond the ends of the supporting rods, and means for sustaining said contact members for yielding movement in a direction longitudinally of said supporting rods 120 and for swinging movement about a center normally beyond the ends of said rods.

3. In a display device, the combination of a case, a rotatable rack movable into and out of the case, guards secured to the rack, pivotally mounted contact arms extending beyond the ends and sides of the rack to contact with the case should the rack be moved inward in any position other than parallel to the back wall of the case, and 130

means for yieldingly connecting said contact arms with the rack.

4. In a display device, the combination of a case, a rotatable rack having supporting bars and movable into and out of the case, yielding arms projecting laterally from the rack at a greater radial distance from the axis of rotation of the rack than the ends of the supporting bars, a support for said yielding arms, and yielding means between said support and the rack that said arms may yield about said support when brought into contact with the walls of the case as the rack is moved inward diagonally and to bodily yield with said support when brought into contact with the case as the rack is moved inward at right angles to the back of the case.

5. In a display device, the combination of a case or cabinet, a rack rotatable with respect thereto, yielding arms pivotally carried by the rack and adapted to contact with the case or cabinet when the rack is moved bodily inward in any rotative position other than parallel with the back wall of the case or cabinet, said arms being mounted for bodily movement longitudinally of the rack.

6. In a display rack, the combination of a case or cabinet, a rack rotatable with respect thereto, contact arms carried by the rack and adapted to contact with the case when the rack is moved inward in any rotative position other than parallel to the back wall of the case or cabinet, said contact arms being yieldingly mounted for bodily movement longitudinally of the rack and having end portions adapted to yield and move in the arc of a circle when they contact with the wall of the case.

7. In a display device, the combination of a case or cabinet, a rack rotatable with respect thereto, a yielding support carried by the rack for yielding movement in a direction longitudinally of the rack, and yielding contact arms pivotally mounted on said yielding support.

8. In a display device, the combination of a case, a rotatable rack movable to and from a position within the case and comprising parallel goods supporting rods, a plunger yieldingly mounted for movement rotatively with and longitudinally of said supporting rods, a contact arm pivotally mounted on said plunger and extending laterally of said supporting rods, and means for yieldingly holding said contact arm in operative position.

9. In a display device, the combination of a case or cabinet, a rotatable rack movable to and from a position within said case or cabinet and having parallel goods supporting rods, a contact device comprising an arm extending laterally of the supporting rods, a supporting member to which said arm is pivotally connected, and means acting on the supporting member to normally maintain said contact arm beyond the ends of the parallel supporting rods and permitting said contact arm to yield bodily in a direction longitudinally of said rods.

In testimony whereof, I have signed my name to this specification, in the presence of two subscribing witnesses.

OSCAR L. SMITH.
